UNITED STATES PATENT OFFICE.

ROSE M. TOMASIELLO, OF NEW YORK, N. Y.

COSMETIC COMPOSITION FOR APPLICATION TO THE HAIR AND SCALP.

No Drawing.

Application filed June 29, 1922. Serial No. 571,798.

To all whom it may concern:

Be it known that I, ROSE M. TOMASIELLO, a citizen of the United States, residing at Bronx, in the county of New York and State of New York, have invented certain new and useful Improvements in Cosmetic Compositions for Application to the Hair and Scalp, of which the following is a specification.

This invention relates to a new article of manufacture, a cosmetic composition in the form of a cream for use in connection with the hair and scalp, and has for its object to provide, in a manner as hereinafter set forth, a composition, for the purpose referred to, formed from compounding a plurality of constituents, to be hereinafter described, providing means which when rubbed on the scalp or hair will act to prevent dandruff, impart vigor and life to the hair, reducing the falling out of the hair to a minimum and further provide an invigorating composition for strengthening and preserving the hair.

A cosmetic composition, in accordance with this invention and for the purpose set forth, is formed from compounding the roots of lily plants, beef marrow, refined petroleum and a suitable perfume if desired, and by way of example, the proportions of the several constituents which form the composition are as follows:

Bulbous root-like portions of a lily plant 4 ounces, beef marrow 4 pounds, refined petroleum 4 tablespoonfuls, and any required quantity of perfume.

The lily plant root employed is the bulb of the ordinary Bermuda easter lily.

The manner of preparing the cream is as follows: —

40 The bulbous root like portion of the lily plant is boiled in water for about half an hour, after which the root is removed and placed on a strainer. The beef marrow is then placed on the strainer and the root and marrow subjected to a straining action 45 by rubbing the said constituents or in any other suitable manner to strain the same. During the straining step the root and marrow are mixed together. After the two constituents have been strained, the petroleum 50 is added thereto and thoroughly admixed therewith. The resulting compound is in the form of a substantially liquid cream and to the latter is added the desired quantity of perfume.

A cosmetic composition, compounded in a manner as hereinbefore set forth, provides a cream which when used on the scalp, will purify and open the pores thereof, preventing dryness of the scalp, thereby overcoming 60 the formation of dandruff and it furthermore invigorates the scalp in such a manner so that the hair is strengthened as well as preserved, under such conditions reducing the falling out of the hair to a minimum. 65

What I claim is: —

A cosmetic composition for application to the hair and scalp consisting of the boiled bulbous root-like portion of a lily plant, beef marrow and refined petroleum and in the 70 form of a substantially liquid cream.

In testimony whereof, I affix my signature hereto.

ROSE M. ^{her} TOMASIELLO.
